UNITED STATES PATENT OFFICE.

ISIDORE SHAPIRO, OF CHICAGO, ILLINOIS.

RUBBER SOLE.

1,118,954.

Specification of Letters Patent.

Patented Dec. 1, 1914.

Application filed May 11, 1914. Serial No. 837,616.

To all whom it may concern:

Be it known that I, ISIDORE SHAPIRO, a citizen of the United States, residing at Chicago, county of Cook, and State of Illinois, 5 have invented a new and useful Improvement in Rubber Soles, of which the following is a specification.

My invention relates to rubber soles to be applied to shoes such as worn by athletes, 10 such soles being desirable on account of their elastic properties, and the object of the invention is to provide improved reinforcing means therefor.

My invention is clearly illustrated on the 15 accompanying drawing in which—

Figure 1 is an under side view of a rubber sole with my improved reinforce applied thereto, and Fig. 2 is a sectional view on plane 2—2, Fig. 1.

20 The sole shown comprises the ball section 10, the heel section 11 and the instep 12, the sole being preferably of a single piece of rubber. Extending adjacent to but set inwardly a distance from the edge of the sole 25 at the ball and heel sections respectively are the grooves 13 and 14 in which are inserted the reinforcing bands 15 and 16. These reinforcing bands may be of any suitable material such as canvas or leather and 30 are preferably set with their outer faces flush with the tread surface of the sole and are vulcanized securely into their grooves to form an intimate part of the sole. By having the grooves inside of the sole edge the 35 sole, when viewed from the sides will have

the appearance of being entirely of rubber. Furthermore, the reinforcing strips will be better protected and can be more intimately vulcanized to the sole. If desired, suction pockets 17 can be provided.

40 The insertion of reinforcing material into rubber soles in the manner described will not impair the elasticity or friction properties of the rubber sole but the sole will be greatly strengthened and wear of the rubber retarded. 45 By vulcanizing the reinforcing material to the rubber such material becomes an intimate part of the sole and will not loosen.

I do not of course desire to be limited to 50 the exact arrangement shown as modifications may be possible which would still come within the scope of the claim which is the following:

A rubber sole having a groove therein 55 parallel with its edge but set inwardly a distance therefrom, and reinforcing material seated entirely within said groove with its outer face flush with the tread surface of the sole and vulcanized into said groove to form 60 an intimate part of the sole.

In witness whereof, I have signed my name to this specification in the presence of two subscribing witnesses, this 5 day of May A. D. 1914, at Chicago, Illinois.

ISIDORE SHAPIRO.
